UNITED STATES PATENT OFFICE.

ARTHUR SIMON, OF MILWAUKEE, WISCONSIN, ASSIGNOR TO THE CUTLER-HAMMER MFG. CO., OF MILWAUKEE, WISCONSIN, A CORPORATION OF WISCONSIN.

CIRCUIT-BREAKER.

1,315,426.

Specification of Letters Patent. Patented Sept. 9, 1919.

Application filed May 22, 1916. Serial No. 99,083.

To all whom it may concern:

Be it known that I, ARTHUR SIMON, a citizen of the United States, residing at Milwaukee, in the county of Milwaukee and State of Wisconsin, have invented new and useful Improvements in Circuit-Breakers, of which the following is a full, clear, concise, and exact description, reference being had to the accompanying drawing, forming 10 a part of this specification.

This invention relates to overload circuit breakers and more particularly to those having a time element.

It has heretofore been proposed to provide a variable time element for circuit breakers and to regulate the current value at which the same are adapted to respond by introducing a regulable opposition to the movement of the solenoid plunger, whereby said factors may be varied jointly to some extent. This expedient, however, as applied to the ordinary type of solenoid produces a circuit breaker which is either unduly sensitive to momentary heavy overloads or else is relatively unresponsive to small but persistent overloads, dependent upon whether the opposition to plunger movement is small or great, it being impossible to lower the current value at which the 20 device will begin to respond without correspondingly curtailing the time element within which actual opening of the controlled circuit may be avoided by receding of the overload peak.

The present invention has among its objects to overcome the foregoing difficulties and to provide a time element circuit breaker of increased sensitiveness to positive and negative variations in current from 30 a predetermined value.

A further object of the invention is that of providing a circuit breaker capable of calibration to provide both an adequate final pull and a prolonged time element during 40 which the same is sensitive to relatively slight negative current variations to prevent tripping thereof.

A still further object is that of enabling ready adjustment of the timing means of 50 such circuit breakers without disturbing the calibration thereof.

Other objects will appear as the description proceeds.

In the accompanying drawing, wherein is illustrated an embodiment of the invention,
55

Figure 1 is a front view, partly in section, of a circuit breaker constructed in accordance therewith; and,

Fig. 2 is a side elevational view of the 60 same.

Referring to the drawing, the circuit breaker comprises a normally closed switch, a solenoid operated weighted lever for tripping the same and a dash-pot for retarding 65 the operation of the tripping means for a predetermined period, the above elements being conveniently mounted upon a suitable insulating panel.

Specifically considered, the switch comprises a stationary contact 1 adapted for engagement by a movable contact 2 riveted upon a supporting arm 3 pivoted at 4 upon a fixed support 5 and biased to closed position by a coil spring 6 wound about said 70 pivot 4 and having one end engaging a lug 7 upon the contact member 2, the other end being bent to rest against the edge of the support 5. A downwardly projecting lug 9 is further attached to the supporting 75 arm 3 to move therewith in proper relation to be engaged by the tripping means for disengaging said movable contact from said fixed contact.

The tripping solenoid includes a winding 80 supported in a magnetic frame 11 and provided with a plunger 12, a non-magnetic tube 13 surrounding said plunger and a magnetic plug 14 stationarily mounted in the lower end of said tube. The plunger is 85 hollow and tapered at its lower end while the face of the plug is flat.

The aforescribed features of solenoid construction all coöperate to insure a plunger pull curve having the particular characteristics desired, viz., a prolongation of that portion of the curve representing a minimum increase in pull, and an adequate increase in pull near the end of the stroke followed substantially at the end of the 100 stroke by an abrupt termination of such increase.

The hollow character of the plunger and consequent distribution of the lines of force therein at a current value approximating 105 that at which the solenoid is designed to

begin its response insures against any subsequent substantial increase in pull due to increase in flux component acting in the direction of motion of the plunger 5 caused by changes in the flux distribution. Moreover by the coöperation of the tapered end of the plunger with the flat faced plug, the reluctance of the magnetic circuit decreases less rapidly during approach of said 10 members than would occur if both surfaces were flat or of such contour as to fit one within the other. Both of these features thus tend to minimize the increase in pull of the plunger, or in other words, to 15 prolong the portion of the stroke having a flat pull curve characteristic. Near the end of the stroke the reluctance decreases more rapidly owing to the rapid shortening of the air gap between the plug and the ad- 20 vance portion of the tapered plunger whereby a sufficiently strong final pull is insured, while the final sealing between the plunger and plug occurs only along a line contact whereby sticking due to residual 25 magnetism is minimized and a ready release insured, this characteristic being represented by an abrupt termination in the rise of the pull curve at the end of the stroke.

The solenoid also has associated there- 30 with a dash pot 15 to retard the movement of its plunger and as will appear, the dash pot is so designed as to oppose the plunger substantially throughout that portion of its stroke characterized by the flat pull curve 35 and to thereupon terminate its restraining effect to permit free movement of the plunger under the rapidly increasing pull exerted thereon at the end of its stroke.

The dash pot includes an oil cup 16 having 40 a fixed cover 17 to which it is secured for support, said cover being fixed to the lower end of the solenoid frame and being fitted about the lower end of the non-magnetic tube 13. The cup has a lateral enlargement 18 45 provided with right angle passages 19 and 20 providing a bypass therefor and said cup is of restricted internal diameter above the lower part of the bypass to receive a closely fitting-piston 21. The piston is connected 50 by a stem 22 to the solenoid plunger and is provided with passages 23 affording communication between opposite ends of the cup. However, the piston is provided on its under side with a disk valve 24 to close said 55 passages upon descent of said piston thereby necessitating displacement of the oil through the bypass which, as will be understood, renders the dash pot effective for retardation of the solenoid plunger during its down- 60 ward travel. When, however, the piston leaves the restricted bore of the cup and passes into the enlarged end of the cup the oil is permitted free passage around the piston with a resulting free final movement of

the solenoid plunger and upon upward 65 movement of the plunger the dash pot is rendered inactive by the free passage of oil through the openings in the piston.

The proportions of the dash pot are such that the piston will travel in the restricted 70 bore during the stroke of the solenoid plunger characterized by the flat pull curve whereas it will enter the enlarged bore as the pull curve commences its abrupt ascent. Thus provision is made for a definite time 75 element or in other words for a definite prolongation of the period in which the solenoid is rendered sensitive to slight negative current variations by reason of its accentuated flat pull curve characteristic. Also, the dash 80 pot is provided with a screw plug 25 enabling regulation of the flow of oil through the bypass whereby said dash pot may be adjusted for variation of the time element.

The tripping lever 26 is pivoted at 27 85 upon a support 28 carried by the solenoid frame 11 and connected at one end by means of a pivoted link 29 to the upper end of the plunger 12 for actuation thereby. Said lever 26 carries an adjustable weight 30 and an 90 L-shaped trigger member 31, preferably of non-conductive material, spaced from the downwardly projecting lug 9 of the switch arm 3 and movable for engaging and tripping the same only after a predetermined 95 movement of said lever, whereas adjustment of the weight has no appreciable influence upon the time element of the switch as determined by the dash-pot setting.

The weight 30 of course determines the 100 sensitiveness of response of the solenoid, or in other words, the sensitiveness of the solenoid to positive current variations, and being adjustable thus provides a convenient means for calibration. Moreover, the weight 105 in any selected position provides a load of substantially constant value irrespective of the angular position of the arm supporting the same whereby the solenoid is unaffected by its movement.

The solenoid winding being connected in the circuit controlled by the switch 2 or an intermediate relay and the above described calibrating and timing means being respectively adjusted for the current value and 115 duration of overload beyond which protection is desired, the operation of the device will be as follows:

Excess of current will at once cause the solenoid to draw down its plunger and thus force the piston of the dash pot downwardly. The stroke of the plunger will thus be retarded to delay tripping of the switch until the dash pot piston passes into the enlarged bore. If the overload then continues the plunger will then be freed from restraint and the magnetic pull thereon will rise rapidly as above described with the re-

sult of accelerating its movement. The lever 26 will thus be operated to impart a hammer like blow to the switch 2 to open the same and thereby effect interruption of the 5 overloaded circuit. This in turn deenergizes the solenoid whereupon the weight 30 restores the arm and solenoid plunger to initial position thereby permitting the switch to close under the influence of its spring. 10 If, however, the current recedes to a given value during the retarded stroke of the plunger the solenoid will release arm 26 before it effects the opening of the switch and said arm will return to initial position under 15 the influence of the weight. And here it is to be noted that owing to the accentuated flat pull curve characteristic of the solenoid it is sensitive to relatively slight negative current variations whereby the device may 20 be calibrated with a minimum allowance for the differences in current values at which the solenoid will respond and release. In other words, the device may be safely calibrated to respond at a current value very closely 25 approximating the maximum permissible current value.

In addition to the hereinbefore described special construction and coöperation of the plunger 12 and the plug 14, the device includes other material advantages. Among 30 these are the exterior location and the construction of the bypass 19 whereby the valve plug 25 may be adjusted without interference with the other elements or adjustments. 35 It is also noted that fluid may be introduced into the dash pot 15 through said bypass 19 merely by removal of the plug 25. Furthermore, the tube 13, which is in fluid tight connection with the cover plate 17, functions 40 to prevent escape of fluid from the dash pot.

What I claim as new and desire to secure by Letters Patent is:—

1. In a circuit breaker, the combination with a switch, of a tripping solenoid there- 45 for of the closed magnetic circuit type, said solenoid including means functioning to preserve during the latter part of the stroke of its plunger the abrupt pull curve characteristic typical of solenoids of such type 50 while accentuating the flat pull curve char-acteristic thereof during an initial part of such stroke, and means opposing operation of the plunger of said solenoid, providing a time element incident to tripping of said 55 switch.

2. In a circuit breaker, the combination with a switch, of a tripping solenoid there- 60 for of the closed magnetic circuit type, said solenoid including means functioning to pre-serve during the latter part of the stroke of its plunger the abrupt pull curve char-acteristic typical of solenoids of such type 65 while accentuating the flat pull curve char-acteristic thereof during an initial part of

such stroke, and separately adjustable means 65 providing respectively for calibration of said solenoid and for a time element incident to tripping of said switch.

3. In a circuit breaker, the combination with a switch, of a tripping solenoid there- 70 for of the closed magnetic circuit type, said solenoid including means functioning to pre-serve during the latter part of the stroke of its plunger the abrupt pull curve character-istic typical of solenoids of such type while 75 accentuating the flat pull curve character-istic thereof during an initial part of such stroke, and separately adjustable means op-posing movement of the plunger of said 80 solenoid, providing respectively for a time element incident to tripping of said switch and for calibration of said solenoid to re-spond at different current values selectively.

4. In a circuit breaker, the combination with a switch, of a tripping solenoid there- 85 for of the closed magnetic circuit type, said solenoid including means functioning to pre-serve during the latter part of the stroke of its plunger the abrupt pull curve character-istic typical of solenoids of such type while 90 insuring a substantially uniform pull of said solenoid throughout an increased initial portion of such stroke and curtailment of its sealing pull, and means opposing operation 95 of the plunger of said solenoid, providing a time element incident to tripping of said switch.

5. In a circuit breaker, the combination with a switch, of a tripping solenoid there- 100 for of the closed magnetic circuit type, said solenoid including means functioning to pre-serve during the latter part of the stroke of its plunger the abrupt pull curve character-istic typical of solenoids of such type while 105 insuring a substantially uniform pull of said solenoid throughout an increased initial portion of such stroke and curtailment of its sealing pull, separately adjustable means 110 opposing operation of the plunger of said solenoid, providing respectively a variable time element incident to tripping of said switch and for calibration of the solenoid to respond at different current values selec-tively.

6. In a circuit breaker, the combination with a switch, of a tripping solenoid of the closed magnetic circuit type, said sole-noid including a fixed magnetic plug and a plunger having adjacent surfaces which 115 are angularly disposed to one another throughout the stroke of the latter, said plunger being of restricted cross sectional area for high saturation thereof, and means opposing operation of said plunger, provid-ing a time element incident to the tripping 120 of said switch.

7. In a circuit breaker, the combination with a switch, of a tripping solenoid of the

closed magnetic circuit type said solenoid including a fixed magnetic plug and a plunger having adjacent surfaces which are angularly disposed to one another throughout the stroke of the latter, said plunger being of restricted cross sectional area for high saturation thereof, and means opposing operation of said plunger, but only during that portion of its stroke characterized by a substantially uniform pull, to provide a time element incident to tripping of said switch.

8. In a circuit breaker, the combination with a switch, of a tripping solenoid of the closed magnetic circuit type, said solenoid including a fixed magnetic plug and a plunger having adjacent surfaces which are

angularly disposed to one another throughout the stroke of the latter, said plunger being of restricted cross sectional area for ready saturation thereof, adjustable means for subjecting operations of said plunger to different degrees of opposition substantially constant throughout each stroke, and independent means opposing operation of said plunger but only during that portion of its stroke which is characterized by a substantially uniform pull.

In witness whereof I have hereunto subscribed my name.

ARTHUR SIMON.
